UNITED STATES PATENT OFFICE.

FRANK J. SPRAGUE, OF NEW YORK, N. Y., ASSIGNOR TO THE SPRAGUE ELECTRIC RAILWAY AND MOTOR COMPANY.

ELECTRO-DYNAMIC MOTOR.

SPECIFICATION forming part of Letters Patent No 321,147, dated June 30, 1885.

Application filed February 27, 1885. (No model.)

To all whom it may concern:

Be it known that I, FRANK J. SPRAGUE, of New York, in the county and State of New York, have invented a certain new and useful 5 Improvement in Electro-Dynamic Motors, of which the following is a specification.

In the operation of a shunt-wound electro-dynamic motor on a circuit of constant difference of potential it is desirable when the motor is started to have a strong field-magnet and little current in the armature-circuit, and then to gradually increase the difference of potential at the armature-circuit terminals, and then to gradually weaken the field-magnet, so as to 10 progressively increase the speed of the motor; and when the motor is running it is desirable, in order to change the speed or power, or both, of the motor, or to maintain the speed constant or practically constant under varying 15 loads, to change the strength of the field-magnet without affecting the armature-circuit, while in other cases, as in some circumstances which arise in the operation of moving motors on electric railways, it is desirable to vary the 20 armature-current without affecting the field-magnet strength.

To enable these various regulations to be readily performed is the object of the present invention.

30 In accomplishing this object I provide means independent of each other for regulating the armature-current and the field-magnet strength, respectively. The armature-regulating means is preferably an adjustable resistance in the 35 armature-circuit, and the regulator for the field-magnet may be an adjustable resistance or other known device or construction for this purpose—such, for instance, as those set forth in my prior applications for patents.

40 My invention is illustrated in the accompanying drawings, in which Figure 1 is a diagram of a motor provided with regulating devices embodying my invention, and Fig. 2 a similar diagram showing a different field-magnet regulator.

45 1 2 are main conductors of a supplying-circuit, preferably a circuit of constant difference of potential, with which I prefer to use my invention. 3 4 is the armature-circuit, and 5 6 the field-circuit of a shunt-wound electro-

dynamic motor A. In the field-circuit 5 6 is an adjustable resistance, B, Fig. 1, and in the armature-circuit 3 4 is an adjustable resistance, C. It will be seen that each of these resistances is controllable independently of the 55 other. Thus to increase the strength of the field-magnet a portion of the resistance B is cut out of circuit, and to decrease its strength more of the resistance B is placed in circuit. Thus the regulation of the field-magnet is performed without affecting the armature-circuit. 60 The current in the armature is similarly controlled without affecting the field-magnet by the adjustment of the resistance C. The regulating means for the two circuits may include, 65 also, a circuit-reverse for each circuit D or D', whereby the current in either circuit is reversed without affecting the other circuit.

The field-magnet regulator shown in Fig. 2 consists of a circular commutator, E, to the 70 blocks of which are made connections 7 7, from the bights of sections into which the field-magnet coils are divided, such sections being connected together into a continuous closed circuit, and each section being wound from 75 end to end of the core, although in the drawings, for convenience of illustration, the sections are placed side by side on the cores. The supplying terminals of the field-coils are connected with the two pivoted arms a a on the 80 commutator E, and by moving said arms upon the commutator the current is reversed in more or less of the field-coil sections, whereby the strength of the field-magnet is varied independently of the armature. As this apparatus 85 also may effect the reversal of the field magnetism, the current-reverser D is here dispensed with.

In the armature-circuit is an adjustable resistance, C, and circuit-reverser D, whereby 90 the armature-circuit is independently regulated, as before.

The reversing-switches may be used to make and break the circuits, or additional circuit-controlling switches may be provided.

The arrow-heads in the drawings show the direction of current in the circuits.

It is evident that my invention is applicable to the armature and main-field circuits of that class of shunt-wound motors having differen- 100

tial coils in series with the armature, although it is set forth with relation to a simple shunt-wound machine.

What I claim is—

- 5 1. A shunt-wound electro-dynamic motor provided with means for varying its armature-current and independent means for varying the strength of its field-magnet, substantially as set forth.
- 10 2. A shunt-wound electro-dynamic motor provided with means for varying the strength of its field-magnet and with an adjustable resistance in its armature-circuit, substantially as set forth.
- 15 3. The combination, with a shunt-wound electro-dynamic motor, of independently-adjustable resistances in its armature and field-circuits, substantially as set forth.

4. The combination, with a shunt-wound electro-dynamic motor, of a circuit-reverser, ²⁰ and an adjustable resistance in its armature-circuit, and means for varying and reversing its field magnetism, substantially as set forth.

5. The combination, with a shunt-wound electro-dynamic motor, of a circuit reverser, ²⁵ and an adjustable resistance in its armature-circuit, and a circuit-reverser and an adjustable resistance in its field-circuit, substantially as set forth.

This specification signed and witnessed this ³⁰
24th day of February, 1885.

FRANK J. SPRAGUE.
